ATTORNEY.

UNITED STATES PATENT OFFICE.

CHARLES E. JOHNSON, OF NEW BRITAIN, CONNECTICUT, ASSIGNOR TO THE AMERICAN HARDWARE CORPORATION, OF NEW BRITAIN, CONNECTICUT, A CORPORATION OF CONNECTICUT.

LOCK.

1,322,697.

Specification of Letters Patent. Patented Nov. 25, 1919.

Application filed June 29, 1915. Serial No. 36,921.

To all whom it may concern:

Be it known that I, CHARLES E. JOHNSON, a citizen of the United States, residing at New Britain, in the county of Hartford and 5 State of Connecticut, have invented a new and improved Lock, of which the following is a specification.

My invention relates more especially to that class of locks in which the bolt is normally projected into locking position, but which will yield to permit the closing of the door to which it is secured, and an object of my invention, among others, is to provide a lock of this kind that shall be extremely 15 simple and cheap in construction and effective in operation, and that shall be secure as against unauthorized use.

One form of lock embodying my invention and in the construction and use of which 20 the objects herein set out, as well as others, may be attained, is illustrated in the accompanying drawings, in which—

Figure 1 is a face view of my improved lock with the cover plate, and tumblers removed, and the barrel cut in section near the lower end thereof.

Fig. 2 is a like view but with the cover plate only removed, the barrel being cut at a greater distance from the lower end than 25 in Fig. 1, the parts being shown in locked position.

Fig. 3 is a like view showing the parts in unlocked position.

Fig. 4 is a detail perspective view illustrating the construction of the barrel.

Fig. 5 is a detail side view of the same with parts cut in section to show the key cylinder.

Fig. 6 is a side view of the lock.

40 In the accompanying drawings the numeral 6 indicates a lock case in which a latch bolt 7 is slidably mounted and pressed outwardly by a spring, in a manner common to structures of this kind. A latch bolt 45 locking slide 8 rests against the latch bolt and is guided in its sliding movements as by means of guide posts 9 projecting through slots 10 in said locking slide. This slide has a bolt locking nose 11 at one end positioned to rest against a shoulder 12 on the latch bolt, and the slide also has a slide locking stud 13. Tumblers 14 are pivotally mounted upon one of the guide posts 9, these tumblers having slots 15 terminating

in slide locking recesses 16, said slots and recesses being adapted to receive the slide locking stud 13 to permit movement of the slide 8 and also to locate it in its retracted position. The latch bolt locking slide forms an important part of my invention as will be 60 hereinafter pointed out.

55 A barrel 17 is rotatably mounted within the case, a key cylinder 18 secured to the barrel forming a part of its rotatable support. The reduced end of this cylinder 65 projects into an opening in the case and a head 19 closely fits the inner wall of the barrel, resting against a flange 20, formed by the overturned edge at the end of the barrel. The body of the barrel projects 70 through an opening in the opposite wall of the case from that in which the end of the key cylinder is located, the two walls of the case thus forming a rotatable bearing 75 for the barrel.

The barrel is cut away as at 21 near its lower end for the reception of the tumblers 14, and a bolt actuator 22 is secured to this end of the barrel as by means of a headed lug 23 fitting a notch 24 in one side of the 80 barrel, the head of the lug resting against the outer surface of the barrel. The reduced end of the key cylinder projects through this actuator, the latter resting against the shoulder formed by the reduced end of the key cylinder and being located between said shoulder and the inner face of the wall of the case against which it rests. A bolt actuating tongue 25, 85 constituting a part of the actuator, extends 90 into an actuating recess 26 in the latch bolt. A knob 27 is secured to the barrel outside of the case.

95 It will be noted that when the locking slide 8 is in its locking position with the nose 11 against the shoulder 12 on the latch bolt, the latter is "dead," that is, it cannot be moved or disengaged from the keeper as by means of an instrument thrust against the beveled end of the bolt, or otherwise. 100 The key is not employed to throw the latch bolt, but serves merely to position the locking slide to lock the latch bolt against movement and thus cause it to become a "dead" bolt or to release the locking slide and thus 105 cause the latch bolt to become a "live" bolt and capable of operation by means of the knob 27.

The parts are operated as follows:

A key inserted in the key cylinder will have its notches and points positioned to move the tumblers so that the stud 13 may 5 pass through the slots 15 into the locking recesses 16, whereby the latch bolt slide will be held in its retracted position, said slide being moved to this position by engagement of the edge of the key within the 10 slide operating notch 28. In this position of the slide the locking projection 11 is removed from engagement with the latch bolt so that the latter may be moved to disengage it from its keeper and this may be 15 effected as by means of the knob 27 by which the barrel and bolt actuator may be turned to operate the latch bolt.

While I have shown and described herein 20 a satisfactory construction of a lock embodying my ideas this may be departed from to a greater or lesser degree and yet be within the spirit and intent of the invention.

I claim:

25 1. A lock including a case, a latch bolt located within the case, a barrel extending into the case, an actuator removably secured to one end of the barrel and extending across it and in engagement with the 30 latch bolt to operate it, and a key cylinder rotatably located within the barrel, and extending through said actuator to form a support therefor.

35 2. A lock including a case, a latch bolt and tumblers located within the case, a barrel extending into the case, an actuator extending across the barrel and comprising one end thereof and one wall of an opening 40 through the side of the barrel into the interior thereof to receive said tumblers, and

a key cylinder rotatably located within the barrel, and extending through said actuator to form a support therefor.

3. A lock including a case, a latch bolt and tumblers located within the case, a barrel 45 extending into the case, an actuator secured to one end of the barrel and extending across it and in engagement with the latch bolt to operate it, and a key cylinder rotatably located within the barrel independently 50 thereof and extending through said actuator into the casing to form one bearing for said barrel.

4. A lock including a case, a latch bolt and tumblers located within the case, a barrel 55 extending through one wall of the case to the interior thereof, said barrel being cut away on one side to receive the tumblers, an actuator secured to the end of the barrel and in engagement with the latch 60 bolt to operate it, and a key cylinder projecting into the barrel and extending through said actuator into said case to form a bearing for one end of the barrel.

5. A lock including a case, a latch bolt 65 and tumblers located within the case, a barrel extending through one wall of the case to the interior thereof and having a notch in its edge, an actuator removably secured to the barrel and having a grooved lug to 70 receive the edges of the notch in the barrel, said actuator projecting to engage the latch bolt, and a key cylinder having a reduced end projecting through said actuator into the case, its opposite end being headed to 75 fit the interior of said barrel.

CHARLES E. JOHNSON.
